DESIGN FOR A RAIL BENDER

Lester O. Becker, St. Louis, Mo., assignor to
Joseph Pavelka, St. Louis, Mo.

Application April 27, 1938, Serial No. 76,763

Term of patent 7 years

To all whom it may concern:

Be it known that I, Lester O. Becker, a citizen of the United States, residing at St. Louis, Missouri, have invented a new, original, and ornamental Design for a Rail Bender, of which the following is a specification, reference being had to the accompanying drawing, forming part thereof.

Figure 1 is an isometric view of a rail bender, showing my new design.

Figure 2 is a longitudinal vertical sectional view taken approximately on the line 2—2 of Figure 1.

I claim:

The ornamental design for a rail bender, substantially as shown.

LESTER O. BECKER.
